Primary Examiner — Marianne Pandozzi(57) **CLAIM**

The ornamental design for a water bottle, as shown and described.

DESCRIPTION

FIG. 1 is a top perspective view of a water bottle according to the present invention;

FIG. 2 is a bottom perspective view of the water bottle of FIG. 1;

FIG. 3 is a right side view of the water bottle of FIG. 1;

FIG. 4 is a left side view of the water bottle of FIG. 1;

FIG. 5 is a front view of the water bottle of FIG. 1;

FIG. 6 is a rear view of the water bottle of FIG. 1;

FIG. 7 is a top view of the water bottle of FIG. 1; and,

FIG. 8 is a bottom view of the water bottle of FIG. 1.

The broken lines in the figures merely illustrate the environment for the water bottle of the present design and therefore form no part of the claimed design.
